TOBACCO WHEEL CONVEYOR AND STRINGING RACK

Cecil Hopkins, Zebulon, N.C.

Application August 13, 1956, Serial No. 603,760

3 Claims. (Cl. 214—5.5)

This invention relates to farm equipment designed to assist and improve the method of handling and stringing tobacco at the tobacco curing barn, to improve and reduce the strenuous labor involved in stringing tobacco, and also to reduce the cost of labor for such operations.

This invention relates to a tobacco conveyor wheel and stringing rack, constructed of a wood frame and a wood conveyor wheel, with handles attached, and also a stringing rack with slide for storage of sticks of strung tobacco.

An object of this invention is to overcome the handicaps involved in the present method of handling and stringing tobacco on sticks at the tobacco curing barn.

The old method requires a lot of strenuous back-breaking labor to everyone involved, in handling and stringing tobacco leaves on sticks at the curing barn. The old method of handling and stringing tobacco from sledges or trucks with the handers handing the bundle of leaves direct to the stringer often times in all directions and levels, making it very difficult for the stringer to get hold of the tobacco, and when a stick of tobacco is completely strung it is necessary for one of the handers to leave the sledge or truck, take the stick from the stringing rack, and carry it to the storage pile. This operation requiring several seconds to complete and also at this time the other handers have to get a stick and put on stringing rack, making it necessary for both handers to be idle for this period of time, and if the handers have the bundles of tobacco leaves ready for the stringer to take, the stringer can cause them to lose considerable time by not taking them, making it necessary for them to hold the bundles for several seconds before taking bundles, also the leaves of tobacco being placed in sledge or truck by the primers or croppers in the field are, most of the time, placed in a very disorderly manner, making it necessary for the handers to lose considerable time in arranging the leaves in a straight order, so that the handers can assemble the leaves in bundles to be handed to the stringer.

It is also an object of this invention to eliminate the problems as described in the old method, and to provide a tobacco conveyor wheel and stringing rack as shown in the drawings, which will improve tobacco handing and stringing as follows: The handers being able to sit on seats and place bundles in clamps in a systematic manner with regularity and at the same level at all times, making it much better, more convenient, and time saving on the handing operation. Also the stringer being able to take bundles of leaves at regular intervals and at the same level at all times, which makes the stringing operation much easier and faster, and also the stringing rack having a trip to be worked by stringer's foot, enabling the stringer to trip the finished stick of tobacco on to a slide ramp adjacent to stringing rack. This ramp being capable of holding several sticks of tobacco is also a labor saver from the old method.

Four people with the aid of this machine can turn out the work of six without the machine.

Other objects and advantages of the invention will be apparent from the following description taken in conjunction with the accompanying drawings wherein:

Fig. 1 is a perspective of tobacco holding mechanism in accordance with the present invention;
 Fig. 2, a section on the line 2—2 of Fig. 1;
 Fig. 3, a section on the line 3—3 of Fig. 2;
 Fig. 4, a section on the line 4—4 of Fig. 3;
 Fig. 5, a section on the line 5—5 of Fig. 2;
 Fig. 6, a section taken on the line 6—6 of Fig. 2;
 Fig. 7, an enlarged fragmentary detail of the tobacco holding clip;

Fig. 8, a side elevation of a tobacco stringing rack in accordance with the present invention;

Fig. 9, an end elevation of the rack of Fig. 8; and
 Fig. 10, a section on the line 10—10 of Fig. 8.

Briefly stated the invention comprises a vehicle having a rotatable turntable with clips along its rim, an adjacent table on which tobacco is adapted to be placed and from which tobacco is taken and placed in the clips on the turntable for removal at a remote position or on the opposite side thereof.

At the point of removal a tobacco stringing rack is located having a pair of spaced upright posts across the upper ends of which tobacco sticks are adapted to be supported one at a time and on which tobacco taken from the turntable is strung. A foot lever is provided for causing the upper ends of such posts to be swung with the tobacco stick onto a pair of inclined spaced rails or supports from which the sticks may be removed after they have accumulated.

With continued reference to the drawings the device of the present invention comprises a framework composed of two pairs of uprights 10 one pair being supported by an axle 11 and wheels 12. The uprights or posts 10 are secured in fixed relation by means of end and side members 13 and 14, a lower cross-brace 15, and a diagonal brace 16.

A pair of parallel upper side members 17 are attached to the uprights 10 and extended horizontally and provide handles by which the vehicle may be moved as well as supports for cross-boards 18 which form a table for the reception of the harvested tobacco. The outer ends of the members 17 are provided with legs 19 connected thereto by means of pivots 20.

Above the transverse brace 15 is mounted a similar brace 21 on the side bar 17, cross-braces 15 and 21 being fixed to the side members 14 and 17. The said cross-members 15 and 21 are provided respectively with openings 22 and 23 in which is located a vertically adjustable post 24, such post having a series of horizontal or transverse openings 25 for the reception of a pin 26, such adjustment being provided in order that the turntable 27 supported on the end of the posts may be vertically adjusted to suit the height of workmen. The table 27 is provided with a depending sleeve 28 in which the upper end of the shaft 24 is received in suitable thrust and side bearings 29 and 30 for reducing friction in order to permit the turntable 27 to be easily rotated.

Around the margin of the turntable are mounted tobacco leaf holding clips of opposed jaw forming side members 31 attached by mounting screws or other fasteners 32 to the turntable 27. The jaws of each pair of side members 31 are urged towards each other by means of a tension spring 33. The leaf gripping members 31 are spaced around the periphery of the turntable except for a small segment 34 to allow a time lapse. In this area 34 a clip 35 is mounted, such clip being adapted to hold a tobacco stick 36 to be carried to the opposite side of the turntable from the handles 17 where it is placed in contact with an inclined stop member 37 mounted by means of a pair of hinged members 38 and a removable-

pin or pivot upon an upright post 40 and being held in an angular position by means of a hook 41 engaging an eye 42. A pair of posts 40 are provided in spaced relation for supporting the tobacco stick 36 across the upper ends, such ends being provided with notches 43, so that a tobacco stick may rest thereon.

The posts 40 are mounted on a shaft 44 carried in the lower ends of spaced upright posts 45 and the lower ends of which are fixed to spaced frame side bars 46 to which uprights 47 and 48 are attached at each side and support inclined upper rails or bars 49 so that the tobacco sticks 36 after they are filled may be discharged thereon. In order to increase the rigidity of the structure the bars 47 are connected by cross-members 50 and 51. The posts 40 across the upper ends of which a tobacco stick is adapted to be supported may oscillate on the shaft 44 to cause the tobacco stick to be discharged from the upper ends of such posts onto the spaced side bars 49. In order to cause this operation a foot pedal in the form of a crank 52 is detachably connected to the end of the shaft 44 in any desired manner as, for example, by a set screw 53. Thus the oscillation of the posts 40 may be from either side of the machine. In order to maintain the posts 40 normally in an upright position a pair of tension springs 54 are attached by eye bolts 55 to the braces 47 and the opposite ends of the springs are connected by eye bolts 56 to the posts 40. A pair of brackets 57 attached to the fixed posts 45 limits the return swinging of the posts 40 beyond upright position.

With the structure thus provided the stringing rack for holding a tobacco stick during and after it is being loaded can be placed on the platform of boards 18 and the device wheeled or otherwise transported to any desired location, for example, to a barn where tobacco is to be cured. The stringing rack may then be placed in a position on the opposite side of the turntable from the table on which the tobacco is piled and the tobacco may be picked up by workmen and inserted in the clips of the turntable.

A turntable 27 may be rotated in any desired manner and for such purpose an endless band or cylinder 58 is attached to the underside of the table 27 and is adapted to be engaged and driven by an elastic drum or roller 59 fixed on a shaft 60. This shaft extends through a plate 61 and its lower end rests in a thrust bearing 62 carried by a plate 63 forming part of a casing for the driving mechanism. The shaft 60 also is carried by an adjustable bracket in the form of a plate 64 mounted between opposed plates 65 and adapted to be secured in fixed position by means of a fastener 66. The shaft 60 is driven by a motor 67 having a motor shaft 68 with its lower end in a thrust bearing 69, such shaft being provided with a V-belt pulley 70 which drives a V-belt 71 and in turn drives a pulley 72 attached to the shaft 60. The plate 63 forms a part of a housing, the upright wall 73 of which is attached to the motor 67 which in turn is fastened to the plate 61 and the housing is also attached to a fixed support 74. A pair of spaced bars 75 are secured by pivots 76 to the bar 74 in the housing 73, the member 74 being provided with a slot 77 in which the shaft 60 and motor 67 are allowed to slide.

In order to maintain the elastic roller 59 in contact with the band 58 which rotates the turntable, a tension

spring 80 is employed having one end connected to a pin 78 on one end of a rectangular member 79 attached to the fixed bar 74, the rectangular member having a pin 78 on each end and the spring having its opposite end connected to the pin 81 on the plate 61 which forms a part of the assembly with which the band 58 and roller 59 are associated. The plate 61 overlies the slot 77. The turntable may be driven clockwise or reversely, depending upon whether the resilient driving drum 59 is on the interior or exterior of the band 58, by reversing the driving mechanism and the tension spring 80.

What is claimed is:

1. For use in a system for handling picked tobacco comprising a vehicular frame, a horizontally disposed turntable journaled on said frame and including a peripheral edge portion extending forwardly beyond one end of said frame, a table on said frame opposite said peripheral edge portion for supporting harvested tobacco leaves thereon, means for rotating said turntable, a plurality of circumferentially spaced resilient clips on said turntable for receiving stems of depending tobacco leaves therein and at least one tobacco stick; a stringing rack comprising a frame including spaced vertical posts disposed transversely of and spaced from the peripheral edge 15 of said turntable including means for supporting a tobacco stick on the upper ends thereof, a pair of downwardly inclined rails in substantial alignment with and spaced from said vertical posts for conveying a loaded tobacco stick away from said posts, and means displaceably supporting said posts in a vertical position and for pivotal movement toward said rails whereby the arcuate path of the upper ends of said posts with a loaded tobacco stick thereon will intersect the general plane of said rails and the stick will be deposited on the rails.
2. For use in a tobacco handling system, a tobacco stringing rack comprising a frame including vertical supports at one end, a pair of posts pivotally mounted on said supports on a horizontal axis of rotation, means on the upper ends of said posts for supporting a tobacco stick 20 transversely thereof, a pair of horizontally disposed rails spaced from and in substantial alignment with said posts, said rail being inclined away from said posts for conveying by gravity a tobacco stick received from said posts, and means mounting said posts in a substantially vertical 25 position and permitting pivotal movement thereof toward said rails whereby the arcuate path of movement of the upper ends of said posts will intersect the plane of said rails.
3. The structure of claim 2 in which said last mentioned means comprises spring means engaged between at least one post and said frame, and a manually actuated force transmitting element operatively connected to said posts for simultaneously moving the same toward said rails in opposition to said spring means.
